DUMP SCOW

Albert J. Dawson, Sewickley, and Alfred C. Leigh, Bellevue, Pa., assignors to The Dravo Contracting Company, a corporation of Pennsylvania

Application January 6, 1933. Serial No. 650,418

6 Claims. (Cl. 114—35)

This invention relates to dump scows, and consists in improvement in the gate-operating mechanism, with the results that the gates are more easily operated, proper closure more accurately and certainly effected, and the mechanism rendered more readily accessible for purposes of maintenance and repair.

In the accompanying drawings, Fig. I is a view in side elevation of a dump scow, such as that to which this invention is applicable. Fig. II is a view of the scow in plan from above. Fig. III is a fragmentary view in cross-section and to larger scale, on the plane indicated at III—III, Fig. II, showing in elevation the gate-operating mechanism of this invention. Fig. IV is a view in horizontal section, on the plane indicated at IV—IV, Fig. III. Figs. V and VI are fragmentary views showing in elevation and in plan, and to still larger scale, a detail. With respect to Fig. IV, Fig. V is a section on the plane V—V. Fig. VII is a view in cross-section, on the plane VII—VII, Fig. IV. Fig. VIII is a view in section, on the plane VIII—VIII, Fig. IV. Fig. IX is a diagrammatic view in side elevation of an assembly of parts found in Fig. VIII. Fig. X is an illustration of a detail, shown in cross-section, on the plane indicated at X—X, Fig. III.

A dumping scow of familiar construction, such a scow as is shown in Figs. I and II, is provided with a succession of pairs of hoppers 1, with downwardly and outwardly inclined bottom walls. These bottom walls slope downward from a ridge on the longitudinal mid-line of the scow. The hull walls of the scow constitute the side walls 2 of the hoppers, and in these hull walls gates 2 are pivoted on horizontally extending axes. Their lower edges swing to and from closure with the sloping floors of the hoppers. This general construction will be manifest on comparing Figs. I, II, III and VII of the drawings.

The gates, when free, swing outwardly under the weight of the burden of material in the hoppers, and operating mechanism is provided for swinging the gates to closed position and securing them in closed position so long as a load is to be sustained.

It will be perceived, on considering particularly Figs. III and VII of the drawings, that the oppositely sloping floors of each pair of hoppers form, as it were, the roof of an underlying chamber. The gate-operating mechanism which hitherto has been the usual one includes a rotatable shaft arranged upon the center line of the scow and in the chamber beneath such roof. Upon this shaft a pair of drums is mounted; a

pair of chains is provided for each of the two oppositely swinging gates of the opposite hoppers; and upon each of the two drums one chain from each of the two opposite gates is wound. A suitable stop is provided to hold the shaft against rotation in gate-opening direction, which stop is retractable, to the end that the gates may in proper time swing open in response to the weight of the load. The gates are swung from open to closed position manually, ordinarily by means of lever and ratchet. The four chains of the two opposite gates extend from the two drums, through openings in the floors of and near the upper ends of the hoppers, and then downward over the floors of the hoppers to the points of connection with and adjacent the lower edges of the gates. The reaches of chain within the hoppers are protected by plates secured in place above them.

By mechanism commonly employed and of the character indicated, it is not possible to achieve accurate and tight closure of the gates under practical conditions of use, and this is a disadvantageous feature, permitting undesired escape from the closed hoppers of some of the material contained in them. The improved gate-operating mechanism of this invention primarily concerns the accurate and complete closure of the gates in repetitive operation under service conditions. Incidentally, the improved mechanism is susceptible to easier operation by muscular power. Furthermore, the operating parts are more readily accessible for purposes of adjustment and repair.

The mechanism of the present invention includes a shaft 3, arranged upon the longitudinal mid-line of the scow and beneath the ridge formed by the meeting of the floors of a pair of opposite hoppers, situated substantially as is the operating shaft of the prior-art structure alluded to above. This shaft 3 of the present gate-operating mechanism does not, however, itself carry the drums upon which the gate-operating chains are wound.

The shaft 3 is provided with a ratchet-wheel 4; and a ratchet 5, pivoted on a stationary part of the structure, is effective by engagement with the ratchet-wheel to hold the shaft against rotation in gate-opening direction.

In detail, the ratchet is compound and includes a proximal member 6, pivoted immediately to a fixed support in the scow structure, and a distal member 5 pivoted to the proximal member. The distal member is provided with a rearward extending arm 7, and a keeper 8, pivoted upon a fixed support (conveniently on the same pin with

- member 6), is capable of being swung alternately to engage and to release the arm 7. The keeper is advantageously of the stirrup form shown and swings over the tip of the rearward extending arm.
- 5 The pivotal center of the union of the members 5 and 6 is in the assembly so far displaced from alignment between the center of pivotal turning of the member 6 and the point of engagement with the ratchet-wheel (and the displacement 10 is such) that, when the keeper is swung aside, the ratchet will under the stress of the load (tending to rotate the shaft) collapse, and allow the shaft to turn. The keeper 8 also is provided with an arm 80, so disposed that it is accessible to be 15 struck a blow by a sledge. When the parts are in the full-line positions shown in Fig. V, a blow struck upon arm 80 effects the swinging of the keeper, with release of the arm 7. Thereupon the ratchet collapses, the shaft turns, and the load, 20 swinging open the gate, escapes. It will particularly be remarked that by such provision the loaded scow may be dumped with greatest ease, and without danger to the attendant who operates it.
- 25 The effective length of the ratchet is adjustable. This feature is realized in making the distal member of the ratchet in two parts which are united in screw-threaded engagement. To the outer of these two parts the reference numeral 5 30 is in the drawings immediately applied. By turning the part 5 upon the companion part the adjustment is effected. In such a necessarily rugged structure this refinement affords minute adjustment in practical form. Adjustability in the effective length of the ratchet is desired, that (the 35 assembly being otherwise complete) the gates when shut may be held by the retaining means precisely in place and without appreciable easing-off.
- 40 A separate drum 9 is provided for each of the gate-operating chains; and, since in usual arrangement each gate is operated by two chains, the whole assembly, with a single shaft 3, is that illustrated in Fig. IV: four drums 9 are symmetrically arranged on opposite sides of the shaft 3, a pair adjacent each end of the shaft 3. Rotation is imparted to the drums by pinions 10, borne by shaft 3, and by gear wheels 11, borne by the drums, and, with Fig. III particularly in view, it will be 45 perceived that rotation of shaft 3 will effect the simultaneous rotation of both pairs of drums 9; that the simultaneous rotation of the drums of each pair will be in uniform direction. The gate-operating chains from opposite gates, diagrammatically indicated in Fig. III by the broken lines 50 12, are oppositely wound upon the opposite pairs of drums 9; and in consequence, the rotation of shaft 3 and the corresponding rotations of the pairs of drums 9 will be either simultaneous gate-closing rotations or simultaneous gate-opening rotations. With Fig. III in view, clockwise rotation of the drums 9 will be gate-opening rotations, and counter-clockwise rotation of the drums will be gate-closing rotations.
- 55 In the gate-operating mechanism now in common use and characterized above, the winding drums are mounted upon the shaft at points relatively remote from its ends. In the mechanism of this invention, the drums and gearing are brought 60 to the very ends of the shaft 3, where they are accessible for purposes of adjustment and repair, at the place indicated by the arrow *a* in Fig. I. Furthermore, by so situating the drums 9, the gate-operating chains 12 (Figs. III and VII) may 65 be brought close to the end walls of the hoppers,

and the protecting plates 13 for the chains may then be secured to and carried by the end walls 14 of the hopper (as is particularly shown in Fig. X), which end walls are or may be bulkheads of the scow (cf. Fig. VII).

It is manifest that the pinions 10 and the gear wheels 11 may be so proportioned as to facilitate gate closure by muscular power.

By the provision of separate drums for each chain of the opposite pairs of gates, there is no interference of one chain with another in winding and unwinding, no irregularities incident to overlapping of chain upon chain, and no consequent irregularity in the swing of the gates of an opposite pair. And it will not then come about that the mechanism will come to a stand with one gate wholly closed and the other still incompletely closed.

The operating mechanism of the invention includes a further feature of adjustment whereby, after the structure has been assembled and the gate-swinging chains anchored to the drums, the effective length of one chain may be adjusted relatively to another, to the end that accurate and complete closure of both gates of the pair 100 and at both ends of each gate shall be effected. This feature of adjustment is particularly shown in Figs. VIII and IX, where it will be seen that the gear-wheel 11 and the drum 9 are united by means of a removable pin 15. This pin penetrates 105 aligned orifices in the webs of the drum and of the gear-wheel. In Fig. IX, it is indicated that, whereas the gear-wheel 11 is equipped with a succession of sixteen circularly arranged and equally spaced pin-holes (shown in full lines), the drum 9 is provided with seventeen equally spaced pin-holes (shown in dotted lines). By this provision, it is possible, withdrawing the pin 15, to make minute shifting of the drum 9 relatively to the gear-wheel 11, and then to secure 110 the two parts together again by inserting the pin in two pin-holes that happen then to have come to alignment. A removable keeper 18 is provided to hold the inserted pin in place during operation.

The drums 9 are advantageously made of such circumferential extent that, within a complete rotation, there will be sufficient chain travel to permit the normal swing of the gate between opened and closed positions. In consequence, there will be no overlying of the chain, turn upon turn, and the precision of the range of swing will not, on such account, be disturbed.

In operation, the gates are closed by the swinging of a hand-lever 16, which is pivoted co-axially with the shaft 3 and which, by means of a dog 17 engaging the ratchet-wheel 4, effects shaft rotation. When in such manner the gates of an opposite pair of hoppers have been closed, the ratchet 5, engaging the ratchet-wheel 4, is effective (keeper 8 being in the full-line position, Fig. V) to secure the gates in closed position. When the scow is to be dumped (dog 17 being withdrawn), a sledge blow upon the arm 80 of keeper 8 swings the keeper to the broken-line position and allows the ratchet 5 to collapse under the thrust of the ratchet-wheel 4, upon which the weight of the load acts, through swinging gate, chains, gear-wheels, and pinions. Thus, automatically on the swinging of the keeper 8, the scow dumps itself. Should inequality develop, in consequence of wear, so that the gates, or either of them, close inaccurately or incompletely, the adjusting device shown in Figs. VIII and IX is readily accessible, at the point indicated in Fig.

I at *a*, to alter the effective length of one chain relatively to the other three chains of each assembly, to the end that the desired evenness and completeness of closure shall be effected. If the 5 gates are not held closed with sufficient tightness, adjustment of the effective length of the ratchet 5 will afford remedy. Furthermore, as has been said pawls, ratchets, dogs, pinions, and gear-wheels, all of them, are readily accessible for 10 purposes of replacement and repair, as well as of adjustment.

We claim as our invention:

1. Gate-operating mechanism for a dump scow including, in association with a pair of opposite hoppers with sloping floors and oppositely 15 swinging gates, a pair of drums, means for rotating the drums in simultaneity, two tension members anchored one to each of said drums and secured at their opposite ends one to each 20 of said gates, and means for adjusting when the parts are organized one drum circumferentially while the other drum continues in relatively stationary position.

2. Gate-operating mechanism for a dump scow 25 including, in association with a pair of opposite hoppers with oppositely swinging gates, a power shaft, a pair of drums, a pair of gear-wheels united, one with each of said drums, and means including the said gear-wheels for transmitting 30 rotation from said shaft simultaneously to the two drums, and a pair of tension members anchored, one to each of said drums and secured at their 35 opposite ends, one to each of the said gates, the union of one of said drums with its companion gear-wheel being adjustable, whereby the relative positions of the two said parts may be altered in circumferential direction.

3. Gate-operating mechanism for a dumping scow including, in association with a pair of opposite hoppers with oppositely swinging gates, a power shaft, a pair of drums, a pair of gear-wheels united, one with each of said drums, and means including the said gear-wheels for transmitting 40 rotation from said shaft simultaneously to the two drums, and a pair of tension members anchored, one to each of said drums and secured at their opposite ends, one to each of the 45 said gates, the uniting means between one of the said drums and its companion gear-wheel including a removable pin penetrating aligned 50 orifices in the two said parts, and such orifices

being so multiplied that the two said parts may be so united when standing in different positions of relative circumferential adjustment.

4. A dump scow with a swinging gate and gate-closing means including a rotatable shaft, means for resisting shaft rotation, such means comprising a ratchet-wheel borne by the shaft and a ratchet pivoted on a fixed support in the scow, the ratchet being of compound structure and including a proximal member pivoted immediately to such support and a distal member pivoted to the proximal member, the distal member being provided with an extended arm, and a keeper pivoted to such support and adapted to swing from a position of engagement to a position of release with respect to the arm with which the distal member of the ratchet is provided, the parts being so proportioned and arranged that when the ratchet is in engagement with the ratchet-wheel and the keeper is in engagement with said arm, stress tending to collapse the ratchet is met and resisted by the keeper.

5. A dump scow with a swinging gate and gate-closing means including a rotatable shaft, means for resisting shaft rotation, such means comprising a ratchet-wheel borne by the shaft, a compound ratchet including a proximal member pivoted to a fixed support adjacent the shaft and a distal member pivoted to the proximal member, and movable on such pivotal mounting between extended and collapsed positions, together with a keeper pivoted to such support coaxially with the proximal member of the ratchet and adapted in the range of its pivotal movement to engage the distal member of the ratchet when the latter is in extended position.

6. A dump scow with a swinging gate and gate-closing means including a rotatable shaft, means for resisting shaft rotation, such means comprising a ratchet-wheel borne by the shaft, a compound ratchet including a proximal member pivoted to a fixed support adjacent the shaft and a distal member pivoted to the proximal member, and movable on such pivotal mounting between extended and collapsed positions, together with a stirrup-shaped keeper pivoted to a fixed support and adapted in the range of its pivotal movement to engage the distal member of the ratchet when the latter is in extended position.
